M. HALLANAN

NONSLIP DEVICE FOR HORSES

Filed Nov. 28, 1924

Michael Halloran

BY
Robert B. Killgore
ATTORNEY

UNITED STATES PATENT OFFICE.

MICHAEL HALLANAN, OF NEW YORK, N. Y.

NONSLIP DEVICE FOR HORSES.

Application filed November 28, 1924. Serial No. 752,768.

To all whom it may concern:

Be it known that I, MICHAEL HALLANAN, a citizen of the United States, residing at New York city, in the county of New York and State of New York, have invented certain new and useful Improvements in a Nonslip Device for Horses, of which the following is a specification.

My invention relates to non-slip devices for horses, of the type which can be readily attached to and detached from the horse's foot by the driver, and is particularly intended for use in connection with the inventions disclosed in my Patents No. 1,207,030, dated December 5, 1916, and No. 1,473,425, dated November 6, 1923, it being my object to provide simplified means for solidly locking the device to a horse's shoe so that it will not loosen in use and to so protect the locking means that said means will not be liable to accidental damage whereby its removal or attachment is rendered difficult. Another object is the more rigid attachment of the body of the device to the horseshoe before a detachable calk plate is secured to the body.

In the drawing Fig. 1 is a view of my improved device secured to a shoe, disclosing the side next to the hoof; Fig. 2, a detail view of the inside of a removable calk plate and locking device; Fig. 3, a view of the device on a horseshoe showing the side next to the ground; Fig. 4, a sectional view of the structure of Fig. 1 on the line 4—4 thereof; Fig. 5, a sectional view of the structure of Fig. 1 on the line 5—5 thereof; and Fig. 6, a view of the structure of Fig. 1 on the line 6—6 thereof.

The device comprises two opposed clamp plates 1 and 2 connected by a turnscrew 3 entering a tapped hole in hubs 4 and 5 on each plate, with the threads in opposite directions, so that by turning the screw the plates can be forced apart or drawn together. To protect the screw-threads against accidental damage the half-round protectors 6 and 7 extend from the tapped hubs and are interposed between the screw and the ground.

The plate 2 consists of a thinned plate or flange 8 adapted to pass between the metal shoe 9 and the hoof and an outer bearing surface 10 provided with calks 11 and 12 adapted to bear on the ground, the shoe en-

tering the groove between the parts 8 and 9. The hub 5 has a boss 13 extended at right angles thereto and is tapped to receive a lock screw 14, the head of which enters a countersink in its outer end and its point entering a longitudinal groove or slot 15 in the screw 3 to prevent the same from turning after the device has been expanded inside a horseshoe.

In the drawing I have shown the opposed plate 1 of the type used where it is desired to make use of a detachable calk plate which can be replaced when worn. It comprises the thinned flange 16 adapted to pass between the shoe and hoof, the threaded hub 4, and the overhanging projection 17, which is a counterpart to the recess 18 in the calk plate 19 shown in Fig. 2. This projection 17 lies on the outside of the shoe which is between it and the flange 16. It is therefore possible to solidly lock the device to a horseshoe before the detachable calk plate 19 is secured in place, whereas in my prior patents the calk plates were used as part of the securing means and which, if loosened in use, allowed the whole non-slipping device to become loose on the horse's foot and most probably lost.

The calk plate 19 has a groove 20 on its inner face adapted to receive the hub of the plate 1 and the end 18 receives the projection 17. The calk plate is secured to the plate 1 by means of screws 21' and 22', the heads of which are countersunk as shown in Fig. 5 whereby the screws are protected from accidental damage. This calk plate 19 has the calks 21, 22 and 23 on its bearing face and is generally placed so as to come on the outside of the hoof, as the greatest wear comes there, in order that the worn parts may be cheaply replaced without having to replace the entire device.

The calk plate groove 20 is provided with a key 24 on the under side of the protector 6 which enters a slot 15 in the turnscrew 3 and prevents rotation of the latter after the device has been locked to a shoe.

In practice each end of the turn screw is provided with three of these longitudinal slots as best shown in section in Fig. 5, so that a slight revolution of the screw will bring one of them under the locking device.

In use the locking screw 14 is loosened and the turnscrew revolved to draw the

plates together, the device is slid into the shoe on the horse's hoof and then expanded until solidly locked thereto after which the lock screw 14 is entered into one of the slots in the turn screw.

If the lock screw 14 is omitted, as it may be if the calk plate form of construction is employed, the calk plate is removed, the clamp plates expanded inside the horeshoe with the projection 17 on the lower face of the shoe, after which the calk plate is secured to the main plate, the key 24 entering a slot in the turn screw to prevent rotation.

By the use of either or both of these locking devices the rotation of the turn screw is prevented and the device cannot become loose in use and lost.

While I have shown both forms of locking device to prevent rotation of the turn screw, in practice but one of these forms is used in the production of my device, preferably the screw form.

By this construction the device will fit either the front or the hind feet of a horse and on either the nigh or off side, making its attachment quick and easy, as no selection is required as in the case of special devices for each foot.

I claim:—

1. A non-slip device for horses, comprising a pair of opposed plates, a hub on each of said plates, said hubs being tapped in opposite directions, a turn screw entering said hubs and provided with a longitudinal slot, and a locking device carried by one of said

plates adapted to enter the screw slot to prevent rotation thereof.

2. A non-slip device for horses, comprising a pair of opposed plates, a hub on each of said plates, said hubs being tapped in opposite directions, a turn screw entering said hubs and provided with a longitudinal slot, a tapped boss on one of said hubs, and a screw entering said boss and adapted to extend into the slot on the turn screw to prevent rotation of the latter.

3. A non-slip device for horses, comprising a pair of opposed plates, a hub on each of said plates, said hubs being tapped in opposite directions, a turn screw, entering said hubs and provided with a longitudinal slot, a countersunk tapped boss on one of said hubs, and a screw entering said boss and adapted to extend into the slot on the turn screw to prevent rotation of the latter and with its head adapted to lie within the countersink.

4. A non-slip device for horses, comprising a pair of opposed plates, a hub on each side of said plates, said hubs being tapped in opposite directions, a turn screw entering said hubs, inwardly extending protectors projecting from said hubs and adapted to lie between the turn screw and the ground, and a locking device carried by one of said hubs and adapted to engage the turn screw to prevent rotation thereof.

In testimony whereof I have affixed my signature.

MICHAEL HALLANAN.
